CLAIM

The ornamental design for a gown, as shown and described.

DESCRIPTION

FIG. 1 is a front elevation view of a first embodiment of a gown, showing our new design;

FIG. 2 is a front elevation view of the first embodiment shown in FIG. 1 in an open or separated state, with the hooks and/or loops (e.g., velcro) on the inside of a front panel of the gown unattached to the hooks and/or loops (e.g., velcro) on the inside of a back panel of the gown;

FIG. 3 is a side elevation view of the first embodiment shown in FIG. 1;

FIG. 4 is a back elevation view of the first embodiment shown in FIG. 1;

FIG. 5 is an elevation view of the inside of the front panel of the first embodiment shown in FIG. 1;

FIG. 6 is an elevation view of the inside of the back panel of the gown of the first embodiment shown in FIG. 1;

FIG. 7 is a front elevation view of a first alternative embodiment of the first embodiment shown in FIG. 1;

FIG. 8 is a front elevation view of a second alternative embodiment of the first embodiment shown in FIG. 1;

FIG. 9 is a front elevation view of the second alternative embodiment of the first embodiment of FIG. 1 (shown in FIG. 8) in an open or separated state, with the hooks and/or loops (e.g., velcro) on the inside of a front panel of the gown unattached to the hooks and/or loops (e.g., velcro) on the inside of a back panel of the gown;

FIG. 10 is an elevation view of the inside of the front panel of the second alternative embodiment of the first embodiment of FIG. 1 (shown in FIG. 8);

FIG. 11 is a front elevation view of a third alternative embodiment of the first embodiment shown in FIG. 1;

FIG. 12 is a front elevation view of a second embodiment of a gown, showing our new design;

FIG. 13 is a front elevation view of the second embodiment shown in FIG. 12 in an open or separated state, with the hooks and/or loops (e.g., velcro) on the inside of a front panel of the gown unattached to the hooks and/or loops (e.g., velcro) on the inside of a back panel of the gown;

FIG. 14 is a side elevation view of the second embodiment shown in FIG. 12;

FIG. 15 is a side elevation view of the second embodiment shown in FIG. 12;

FIG. 16 is a back elevation view of the second embodiment shown in FIG. 12;

FIG. 17 is an elevation view of the inside of the front panel of the second embodiment shown in FIG. 12;

FIG. 18 is an elevation view of the inside of the back panel of the gown of the second embodiment shown in FIG. 12;

FIG. 19 is a front elevation view of a first alternative embodiment of the second embodiment shown in FIG. 12;

FIG. 20 is a front elevation view of a second alternative embodiment of the second embodiment shown in FIG. 12;

FIG. 21 is a front elevation view of the second alternative embodiment of the second embodiment of FIG. 12 (shown in FIG. 20) in an open or separated state, with the hooks and/or loops (e.g., velcro) on the inside of a front panel of the gown unattached to the hooks and/or loops (e.g., velcro) on the inside of a back panel of the gown;

FIG. 22 is an elevation view of the inside of the front panel of the second alternative embodiment of the second embodiment of FIG. 12 (shown in FIG. 20);

FIG. 23 is a front elevation view of a third alternative embodiment of the second alternative embodiment of the second embodiment of FIG. 12 (shown in FIG. 20);

FIG. 24 is a front elevation view of a third embodiment of a gown, showing our new design;

FIG. 25 is a front elevation view of the third embodiment shown in FIG. 24 in an open or separated state, with the hooks and/or loops (e.g., velcro) on the inside of a front panel of the gown unattached to the hooks and/or loops (e.g., velcro) on the inside of a back panel of the gown;

FIG. 26 is a side elevation view of the third embodiment shown in FIG. 24;

FIG. 27 is a side elevation view of the third embodiment shown in FIG. 24;

FIG. 28 is a back elevation view of the third embodiment shown in FIG. 24;

FIG. 29 is an elevation view of the inside of the front panel of the third embodiment shown in FIG. 24;

FIG. 30 is an elevation view of the inside of the back panel of the gown of the third embodiment shown in FIG. 24; FIG. 31 is a front elevation view of a first alternative embodiment of the third embodiment shown in FIG. 24; FIG. 32 is a front elevation view of a second alternative embodiment of the third embodiment shown in FIG. 24; FIG. 33 is a front elevation view of the second alternative embodiment of the third embodiment of FIG. 24 (shown in FIG. 32) in an open or separated state, with the hooks and/or loops (e.g., velcro) on the inside of a front panel of the gown unattached to the hooks and/or loops (e.g., velcro) on the inside of a back panel of the gown; FIG. 34 is an elevation view of the inside of the front panel of the gown of the second alternative embodiment of the third embodiment of FIG. 24 (shown in FIG. 32); and, FIG. 35 is a front elevation view of a third alternative embodiment of the third embodiment of FIG. 24. Portions shown in broken lines form no part of the claimed design. A symbolic break in length is shown in FIGS. 7, 11, 19, 23, 31, and 35. The appearance of any portion of the gown between the break lines form no part of the claimed design.
